R. HÖING

RAIL PLATE

Filed Aug. 24, 1921

Fig. 1.

Fig. 2.

Inventor:

Rudolf Höing
by J. K. Reinhardt
Attorney.

UNITED STATES PATENT OFFICE.

RUDOLF HÖING, OF ESSEN, GERMANY.

RAIL PLATE.

Application filed August 24, 1921. Serial No. 494,889.

(GRANTED UNDER THE PROVISIONS OF THE ACT OF MARCH 3, 1921, 41 STAT. L., 1313.)

To all whom it may concern:

Be it known that I, RUDOLF HÖING, a citizen of Germany, residing at Essen, Germany, have invented certain new and useful Improvements in Rail Plates, for which I have filed applications in Germany, March 7, 1918; Belgium, March 8, 1921; Holland, March 30, 1921; France, March 8, 1921; Czechoslovakia, March 30, 1921; 10 England, January 10, 1921, of which the following is a specification.

My invention relates to rail plates and in particular to plates of the kind in which an additional support of the rail on the 15 sleeper is provided by bent portions, which penetrate into the sleeper.

In the drawings accompanying this specification and forming part thereof, an embodiment of my invention is illustrated by way 20 of example. In the drawings

Fig. 1 is a vertical section and

Fig. 2 a plan view of a rail and sleeper provided with my improved plate.

The plate *b* for the rail *a* is at first bent 25 upwards at its lateral edges, so that a face *f* is formed which is engaged by the spike head. On this bent portion there is formed a downward bent portion *c*, which is sharpened at *h*. The heads of spikes *d*, on being 30 driven, are forced against the inclined faces of the plates with their corresponding faces *c*, so that the bent edges of the plate are resiliently bent downwards and penetrate into

the sleeper with their edges *h*. In this manner, the plate *b* is firmly connected with the 35 sleeper. The resilient double bent ends of the plate resiliently support the spike head, so that it does not become loose in the sleeper. Preferably, some play toward the center of the rail is provided at the holes *g* 40 through which the spikes pass. It is also advisable to so form the plate that it is spaced away from the sleeper at point *i*.

I claim:

1. A sheet metal tie plate for railways 45 comprising a flat middle portion, two lateral portions bent into V-shape adjoining said middle portion and a spike hole on either side of said middle portion close to each lateral portion.

2. A sheet metal tie plate for railways comprising a middle portion in the shape of a flat channel with diverging side walls and a lateral portion extending at an acute angle 55 from and in opposite direction to each side wall, said middle portion being provided with spike holes next to said side walls.

3. A sheet metal tie plate for railways comprising a middle portion in the shape of a flat channel with diverging side walls and a lateral portion extending at an acute angle 60 from and in opposite direction to each side wall across and below the plane of said middle portion.

In testimony whereof I affix my signature.

RUDOLF HÖING.
